UNITED STATES PATENT OFFICE.

JOHN KANGLEY, OF STREATOR, ILLINOIS.

MINING-MACHINE.

SPECIFICATION forming part of Letters Patent No. 412,262, dated October 8, 1889.

Application filed June 29, 1888. Serial No. 278,598. (No model.)

To all whom it may concern:

Be it known that I, JOHN KANGLEY, of the city of Streator, in the county of La Salle and State of Illinois, have invented certain new and useful Improvements in Mining-Machines; and I do hereby declare the following to be a full, clear, and exact description of the same, reference being had to the accompanying drawings, forming a part of this specification, and to the letters of reference marked thereon.

This invention relates to that class of coal cutting or mining machines designed more especially for operating on the long wall or continuous face system wherein a horizontal cut is made at or near the lower edge of the vein and along the full length of the gallery; and it has for its object to provide a strong, durable, and compact machine capable of making a cut inward beneath the vein and along the face of the latter, with special provision for cleaning the cut and removing the material detached by the cutters; also, for actuating, holding, and feeding the cutter, all as hereinafter more fully described, and pointed out in the claims.

In the accompanying drawings, Figure 1 is a top plan view of the improved machine. Fig. 2 is a side elevation of the machine. Fig. 3 is a bottom plan view of the frame of the machine, showing part of the gearing. Fig. 4 is a front end view of the machine. Fig. 5 is an enlarged view of the clearing mechanism detached. Fig. 6 is a detail view illustrating a section of the clearing chain and scraper applied thereto. Fig. 7 is a view in perspective of one of the props and rail-clamps. Fig. 8 illustrates in detail one of the cutters.

Similar letters of reference in the several figures indicate the same parts.

The letter A designates the frame of the machine, formed of metal or other suitable material and supported upon two sets of wheels A A', the wheels A on the inner side having plain faces resting on the floor of the gallery, while the outer wheels A' are each formed or provided with double flanges embracing and riding upon a rail A², which latter is placed in position parallel with the face of the vein or wall and detachably secured and held in place by a novel form of clamp

composed of two sections, the one a constituting a chair extending beneath the rail and provided with a shoulder a' on one side fitting against the side and embracing the flanged base of the rail, while the other end is provided with an outwardly-inclined flange or shoulder a². The co-operating section a³ is adapted to fit against the inner face of the rail at one end and against the inclined shoulder a² of the opposite section, so that when placed in position and pressed down the section a³ will be forced and held tight against the inner face and upon the flanged base of the rail, at the same time drawing the other section a firmly in contact with the outer face of the rail. To insure the proper placing and more accurate holding of the two sections a a³ together and upon the rail, the section a³ is formed or provided with one or more lugs a⁴ passing beneath the rail. The shoe or chair thus formed is clamped upon and the rail firmly held in place by an extension-prop a⁵, resting upon, connected to, or engaging the section a³, so that when placed in position and the upper section of the prop is extended or forced upward against the top of the gallery or other rigid support the shoe will be clamped upon the rail and at the same time held firmly in place upon the floor or other support beneath the rail, so that it will be practically impossible either to disengage or loosen the rail or displace the rail or chain until the post or prop is shortened or otherwise released. Several of these props and chains located at suitable distances apart are employed for sustaining the rail in position, and as the machine advances a section of rail is added in advance of that upon which the machine rests while at work. The sections a³, to which the props are applied, are located on the outer side of the rail, so that the machine can pass without weakening contact therewith.

All the operating mechanism of the machine is supported upon the frame or carriage A, and comprises a cutting mechanism, a clearing mechanism, a feeding mechanism which operates to advance the entire frame, and a motor for driving the several mechanisms, as will presently appear.

The cutting mechanism comprises a cutter-

bar B, projecting laterally from the inner side of the frame, mounted to rotate in boxes b, the latter supported in ways or bearings b' in the rear end of the frame. The bearings 5 b' are arranged in castings b², bolted or otherwise secured to the rear end of the frame A, and are located in a plane at or slightly below the axle of the inner supporting-wheel, with the rear end of said bearings or ways 10 open to permit the insertion or withdrawal of the boxes b and the cutter-bar. The outer or working portion of the cutter-bar is made in the form of a frustum of a cone with the base toward the machine, and is provided with 15 radial or other sockets for the reception of the shanks of cutters b⁴. The cutters are spirally arranged about the periphery of the conical bar, so that as the latter is rotated and advanced the strain will at all times be equal. 20 The cutting-blades are formed with diagonal cutting-faces—that is to say, with their cutting-faces inclined in two directions radially and tangentially to the cutter-bar, so that the highest and most advanced point on the edge 25 will be toward the outer end of the cutter-bar. Moreover, the spiral arrangement of the series of cutters is such relative to the direction of rotation of the bar that they will tend to advance or draw the bar inward as 30 the latter is rotated. The object in thus constructing the cutter with diagonal cutting-faces and arranging them spirally upon the bar is to assist in holding the bar in line and in a measure counteract the tendency to lateral movement of the rear end of the machine 35 occasioned by the pressure upon the face of the cutters as the machine is advanced or carried forward.

In order to maintain the general level of 40 the floor, especially where the inner supporting-wheels run, the tapering or conical cutter-bar is disposed with its axis inclined to the horizontal sufficiently to bring the lower surface of the bar or outer ends of cutters in a 45 horizontal plane or level with the floor-line.

The boxes b, in which the cutter-bar is supported on opposite sides of the frame, are held in place and removably secured in the bearings b' by means of a block b⁵ and key 50 b⁶, the former securely held between the ways by a bolt and the key interposed between said block and the side of the box. To withdraw or insert the cutter-bar it is only necessary to remove the blocks and keys, when the bar and 55 its boxes can be slid back through the open end of the ways or supporting-frame.

The clearing mechanism located in rear of the cutter-bar and substantially parallel thereto is designed to remove or withdraw from 60 the cut the chips, &c., detached by the cutters. It comprises a traveling belt or chain C, supported in rear of the cutter on a bar C', the latter detachably secured to the main frame A. This belt or chain is provided with 65 a series of scrapers or blades c, and is rotated in the direction indicated by the arrow,

Fig. 1, around a supporting-pulley c', mounted in bearings in the end of bar C', and a driving-pulley C², mounted in the main frame A. The bar C' is adjusted longitudinally to 70 tighten the belt or extend the clearer by a screw c² or equivalent device on the frame and is held firmly in adjusted position by bolts c³.

Instead of securing the scrapers or blades 75 c rigidly upon the traveling belt or chain, I prefer to make the attachment such as to permit the blades to be tilted in a manner to discharge or release the chips drawn from the cut in rear of the cutter and to prevent them from carrying the chips back into the cut. To this end and as one illustration of the method of carrying this feature into practice I hinge or pivot the scrapers upon the belt or a link of the chain, as at c⁶, and locate a shoulder 85 or stop, as at c⁷, in position to engage and support the scraper in operating—that is to say, when standing vertically the weight of the lower portion of the scraper serving to hold it vertically, while the shoulder c⁷ prevents it 90 from swinging backward as it traverses the cut. A track or bar c⁸ is arranged so as to engage an arm or projection c⁹ on each scraper to tilt the latter after it has emerged from the cut and to hold it elevated during its passage into the cut in rear of the supporting-bar C'. When the arm or projection c⁹ passes off the track c⁸, the scraper at once drops down into vertical position, with its lower edge below the general level of the chain or belt and 95 in position to engage and carry out the material lying in the bottom of the cut.

The feeding mechanism comprises a drum D, mounted in bearings on the forward end of frame A, to which is attached a rope or 100 chain D', the other end whereof is connected to a post or other support in advance of the machine. On the shaft d of the drum is mounted a loose worm-wheel d', with which engages a worm d² on shaft d³, the latter carrying two loose gear-wheels d⁴, engaging pinions d⁵ on a driving-shaft d⁶. The pinions d⁵ are of different diameters, as are also the gears d⁴; hence the latter are driven at different speeds, and either set of gears may be 105 caused to rotate the shaft carrying the worm d². A double clutch-section d⁷, riding on a spline, is interposed between the clutch-sections formed on the proximate faces of wheels d⁴, so that as the clutch-section d⁷ is shifted 110 into engagement with either one of or the other of the wheels d⁴ the worm will be driven faster or slower and the rate of speed correspondingly augmented or diminished, and when the clutch-section d⁷ is held clear of 115 both wheels the motion of the worm will be suspended. A clutch d⁸ is interposed between the shaft d, carrying the winding-drum, and the worm-wheel d' for releasing the drum from the driving mechanism, so that the rope 120 or chain can readily be removed or drawn off.

The cutting, clearing, and feeding mechan-

isms are all driven from a motor E, preferably an engine, driven by compressed air or other fluid pressure. The cylinders E' of the motor are mounted upon the forward portion of the frame A in rear of the winding-drum, while the main driving or crank shaft E² is supported in bearings e, mounted upon the castings b² above the cutter-bar. To the crank-shaft E², and on opposite sides of the 10 crank, are secured pinions e', which mesh with corresponding gear-wheels e² on a counter-shaft e³, having bearings or castings b³.

Motion is given to the cutter-shaft by means of pinions b¹⁰, gearing with wheels e², while 15 the feeding mechanism and clearing devices derive motion from a bevel-gear f on the counter-shaft e³, said bevel-gear meshing with a bevel-gear e⁴ on the driving-shaft d⁶ of the feeding devices and with a bevel-gear e⁵ on 20 shaft e⁶, which latter is connected through bevel-gears e⁷ with the shaft carrying the driving-pulley C² of the clearing devices.

With a machine of this character, in which the cutter-bar is projected from the side and 25 the feed or progressive movement is effected by drawing the machine bodily forward, a great strain is brought upon the cutter-bar in a direction tending to twist the rear end of the machine away from the cut, and at the 30 same time to cramp or jam the cutter-bar in its bearings. By means of the flanged wheels working on a rail on the outer side of the machine lateral movement of the latter is prevented, and the tendency in that direction 35 is in a measure counteracted by the spiral arrangement and form of the cutter. To relieve the cramping action of the cutter-bar in its bearings, two driving-wheels e² are employed and arranged to engage pinions 40 mounted upon the cutter-shaft between but in proximity to the bearings, and the counter-shaft carrying said wheels e² is arranged in front of the cutter-bar, so that as the boxes and pinions wear they may be forced up by 45 the keys b⁵ and held in engagement with wheels e².

As is obvious, a clearing mechanism such as shown herein may be employed in connection with other forms of cutting mechanisms for drawing the chips out from in rear of the cutter and depositing them outside the face of the wall or cut and in rear of the machine.

As hereinbefore stated, the forward end of 55 the rope or chain by which the machine is driven forward may be attached to any suitable stationary object; but I prefer to secure it in the following manner:

An extensible jack or post F, adapted to be 60 clamped between the floor and a support above, is provided with a vertical slot or way f² for the reception of a block f³, carrying a screw f⁴ or equivalent adjusting device, to which the end of the rope is attached by a 65 swivel-connection f⁵. The rope having been drawn off the drum, the post F is located and

secured in position in front of the machine, the end of the rope attached to the adjustable member f⁴, and the rope is drawn taut. The block f³, carrying the adjusting device 70 to which the rope is attached, is permitted vertical movement upon the post to accommodate itself to irregularities in the surface over which the machine travels and to permit the end of the rope to be elevated as the 75 machine approaches.

In operating the machine the rail supporting the outer side thereof is laid longitudinally with the face of the coal and at a distance sufficient to admit of the free passage 80 of the machine along the face of the coal, and yet as close to the face as is consistent with that purpose, in order that the mining or cutter bar may enter as deeply as practicable beneath the vein. The rail is then 85 made fast and kept in place by the application of the shoes and jack-screw posts, the latter making contact at their tops with the roof of the mine or other overlying support and resting at their lower ends upon the 90 clamping-section of the shoe, so that when pressure is applied the roof and floor of the mine furnish points of resistance whereby the posts are rendered rigid and the rail is held firmly in position without the use of ties 95 or cross-pieces of any kind. An initial opening or cut is prepared for the insertion of the cutter-bar and clearing devices at the base of the vein, where the machine is started and the latter mounted with its flanged wheels 100 on the rail, the plain-faced wheels resting on the floor of the mine. Steam or air is conducted to the motor through flexible pipes leading from the source of supply in the entries to the face of the workings when they 105 are attached to the inlet-ports of the valves in the cylinders. The engine or motor being set in motion, the cutter-bar is rotated and the machine advanced by the winding up of the rope or chain, the rate of speed being adjusted or controlled by the shifting-clutch and differential gears. As the machine progresses, the chips made by the cutter fall in rear of the cutter-bar and are drawn outward 115 from the cut by the scrapers or buckets upon the clearing device. When the machine has advanced the length of the wall, a rail is shifted forward and secured in position, the anchor or post to which the rope was attached is loosened and carried forward and fixed in 120 position, the drum is released by the clutch, and the cable drawn off and attached to the anchor, when the machine is in condition to operate as before.

Having thus described my invention, what 125 I claim as new is—

1. In a machine such as described, the combination, with the traveling carriage and the cutting mechanism supported upon and projecting laterally therefrom, of a clearing mechanism supported in rear of the cutter, the same comprising an endless belt passing 130

- around a supporting-pulley near the outer end of the cutter, and a series of pivoted scrapers or blades depending from said belt on horizontal pivots, substantially as described.
5. 2. In a machine such as described, and in combination with the traveling carriage and cutter-bar mounted thereon and projected beyond the sides, a traveling-belt support parallel with the cut and in rear of the cutter and provided with pivoted scrapers depending below the belt, a support on the belt for each scraper, and a bar for engaging the scrapers to tilt the latter, substantially as described.
15. 3. In a machine such as described, and in combination with the cutting mechanism thereof, a clearing mechanism comprising an endless belt or chain mounted to traverse the cut in rear of the cutting mechanism and provided with a series of blades or scrapers pivotally connected to said belt, shoulders to engage and hold said blades in operative position, and a track-engaging shoulder on the blades to tilt the latter and hold them elevated as they enter the cut, substantially as described.
4. In a machine such as described, and in combination with the cutting mechanism thereof, an endless belt supported to travel parallel with the line of cut and located in rear of the cutters, scrapers or blades pivoted to said belt and depending therefrom, and a track or rail engaging said scrapers to discharge their load and hold them elevated when entering the cut, substantially as described.
35. 5. In a machine such as described, the combination, with a rotary cutter-bar mounted upon and projecting beyond the side of a traveling carriage, of an endless belt encircling a roller supported in rear of the cutter-bar, mechanism for driving said belt, so that the portion next the cutter-bar shall move in a direction from the outer end of the bar toward the mouth of the cut, a series of pivoted blades or scrapers mounted upon said belt, and a bar engaging the scrapers after they emerge from the cut to discharge the material, substantially as described.
45. 6. As a means for detachably securing the guide-rail for a mining-machine in position, a shoe or chair formed in sections, and a jack or extensible prop interposed between the shoe and a superposed support and operating to clamp and hold the shoe and rail firmly in position on the floor, substantially as described.
55. 7. In combination with the rail and the shoe engaging the same, a jack-screw or extensible prop resting upon said shoe and interposed between the latter and a superposed support, substantially as described.
65. 8. In combination with the rail, a sectional shoe, one member provided with a shoulder to engage the flange on one side, a cross-bar extended beneath the rail and an inclined
- shoulder, the other section fitting between said inclined shoulder and the rail, and a post resting upon said last-named section and engaging a superposed support to clamp the sections onto the rail and hold them firmly in place on the floor, substantially as described.
9. In combination with the rail, the shoe formed in two sections, the one passing beneath the rail and provided with a bearing for engaging the rail and a shoulder on the opposite side of the rail, the other section fitting between said shoulder and rail and provided with lugs projecting beneath the rail, and a prop resting upon said second section, with means for pressing upon a superposed support to clamp the two sections together and hold the chair and rail firmly in position, substantially as described.
10. In combination with a coal-mining machine of the character described, wherein the cutting devices are mounted upon a traveling carriage supported and guided upon one side by a rail, and in combination therewith, a series of shoes engaging and supporting said rail, and a corresponding series of props, each resting upon one of said shoes and against the roof or a superposed support, substantially as described.
11. The combination, with a machine of the character described, wherein the cutting mechanism is mounted upon a traveling carriage, which latter is drawn or carried forward by means of a rope or chain wound upon a drum, the latter supported upon said carriage, of a movable jack or post provided with a longitudinal movable block, and a tension device supported on said block and adapted to receive and hold the end of the rope or chain, substantially as described.
12. In combination with a mining-machine such as described, an extensible prop, a block movable vertically in guides in said prop and carrying a tension device—such as a screw—to which the rope for feeding the carriage forward is attached, substantially as described.
13. In a mining-machine such as described, in which the feeding and cutting mechanism are mounted upon a traveling carriage, the combination of the winding-drum and its shaft, the worm-wheel, the clutch for connecting said worm-wheel to the drum, the worm engaging the worm-wheel, the driving-shaft, and the two sets of gears, with double clutch interposed between the driving-shaft and worm-shaft, substantially as described.
14. In a mining-machine such as described, in which the feeding, cutting, and clearing mechanisms are mounted upon a traveling carriage, and in combination therewith, the counter-shaft, gear-wheels on said counter-shaft connecting and transmitting motion from the pinions on the main or crank shaft to the rotary cutter, and a bevel-gear secured to said counter-shaft and engaging two gears.

located on opposite sides thereof, the one actuating the clearing mechanism and the other the feeding mechanism, substantially as described.

5 15. In a machine such as described, the combination, with the rotary cutter-bar mounted in bearings on a movable carriage, of a series of cutters spirally disposed about the periphery of the bar, each of said cutters

being formed with a diagonal cutting face or edge from the outer side rearwardly and toward the axis of the cutter-bar, substantially as described.

JOHN KANGLEY.
